United States Patent Office.

THOMAS JEFFERIS, OF COUNCIL BLUFFS, IOWA.

Letters Patent No. 91,940, dated June 29, 1869.

HEATING-DRUM.

The Schedule referred to in these Letters Patent and making part of the same.

To all whom it may concern:

Be it known that I, THOMAS JEFFERIS, of Council Bluffs, Pottawatomie county, State of Iowa, have invented a new and useful Improvement in Heat-Distributors for Stove-Drums; and I do hereby declare the following to be a full, clear, and exact description of the same, which will enable others skilled in the art to which my invention appertains, to make and use the same, reference being had to the accompanying drawings, forming part of this specification, in which—

Figure 1, Sheet I, represents a side elevation of a rectangular heating-drum, having horizontal flues, and showing my improved distributor applied thereto;

Figure 2, Sheet I, represents an edge view of the same;

Figure 3, Sheet I, represents a perspective view of the drum and distributor;

Figure 4, Sheet I, is a transverse section of fig. 3, through the plane of the line xx ;

Figure 5, Sheet II, is a side view of a cylindrical drum, showing the distributor in dotted lines;

Figure 6, Sheet II, is a perspective view of the same;

Figure 7, Sheet II, shows an end elevation of the cylindrical drum; and

Figure 8, Sheet II, is a plan view of a distributor for a heating-drum, having vertical flues.

Similar letters of reference indicate corresponding parts in the several figures.

This invention relates to stove-drums, and has for its object to distribute the heat equally throughout their entire inner surface.

The invention consists in the arrangement of metal plates, having suitable slots or perforations within the drum, between the heat-supply and discharge-pipes.

In fig. 1, Sheet I, is represented a rectangular drum, O , provided with the bent supply-pipe A , and discharge-pipe A' , arranged upon the bottom and top respectively.

B is a series of horizontal flues, for the passage of air; and

D is a door upon the narrow side of the drum, through which access may be had to the interior of the same.

In this example of my invention, two distributors are employed, marked K .

They are composed each of a sheet, or other metal plate, provided with a series of parallel slots, x , as shown in fig. 4.

These plates K are arranged above and below the series of air-flues B , and the heat-supply and discharge-pipes A A' .

It is designed to so construct the distributors, that they may either extend the whole width of the drum,

or only to the outside rows of the flues B , as shown in figs. 1 and 3.

The distributors may be either permanently secured in place, or adapted to slide through the sides of the drum, as desired.

The drum may have any desired capacity above that of the pipes A A' , but the openings X in the distributor must have, in the aggregate, a draught-capacity at least equal to that of the pipes A A' , with an addition thereto, if desired, of from twenty-five per cent., to one hundred per cent., (according, in inverse proportion, to the force of the draught in the flue, or chimney,) for heat-expansion.

The openings in the distributors may be of any preferred shape.

By this arrangement, the heated currents entering through the pipe A' , will be arrested by the lower plate K , and allowed to pass only through the openings X ; and as these are arranged at intervals across, or nearly across the drum, the ascending currents will be evenly distributed throughout the entire drum, finding escape only through the openings in the upper plate.

In drums, as ordinarily constructed, the heated currents ascend centrally thereof, and only those portions are heated which lie in line with the supply and discharge-pipes.

In fig. 5, Sheet II, a cylindrical drum, G , is shown, composed of an inner and outer cylinder, of unequal diameters, arranged concentrically with each other, the supply and discharge-pipes A and A' being placed at opposite ends.

One end of this drum is supported upon the stove, or other heater, by means of the short support J .

In a drum of this construction, the plates K are of annular form, and secured, at a suitable distance apart, between the inner and outer cylinders, and between the pipes A A' , as shown in dotted lines.

Each plate is provided with a series of concentric openings, xx , as shown in dotted lines, fig. 7.

Having thus described my invention,

What I claim as new, and desire to secure by Letters Patent, is—

The arrangement, within the heating-drum, of the perforated heat-distributing plates K , with relation to the air-flues, and heat-supply and discharge-pipes A A' , substantially as described, for the purpose specified.

THOMAS JEFFERIS.
